SHIELD BUCKLE

Filed Sept. 15, 1928

P.M. Swindler, Inventor
C. Snow & Co., Attorneys.

UNITED STATES PATENT OFFICE

ROBERT M. SWINDLER, OF OTTAWA, KANSAS, ASSIGNOR OF ONE-HALF TO WILLIAM T. URE, OF FLORENCE, KANSAS

SHIELD BUCKLE

Application filed September 15, 1928. Serial No. 306,210.

This invention aims to provide a simple means whereby a strap may be held securely within a buckle, it being possible to open the buckle readily, and release the strap upon occasion.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Figure 1 is a plan wherein the buckle has been opened;

Figure 2 is a longitudinal section wherein parts are in elevation;

Figure 3 is a cross section on the line 3—3 of Figure 2.

The buckle forming the subject matter of this application includes a base member 1, in the form of a plate, provided with a stud 2 or equivalent, indicated at 2. The base member 1 is provided at one end with a loop 3, the opening in the loop being designated by the numeral 4. At its opposite end, the base member 1 has parallel arms 5 provided with inwardly prolonged extensions at 6 having fingers 7 disposed at right angles to the plane formed by the parts 6, the fingers 7 terminating in over-hanging keepers 8 which extend inwardly toward each other, the keepers 8 being located in a plane parallel to the plane in which the extensions 6 are located.

The numeral 9 marks a guard, in the form of a plate, provided at one end with an eye 10.

The end bar of the loop 3 is mounted in the eye 10, the guard 9, thus, being hingedly connected to one end of the base member 1. The guard 9 has a depressed intermediate portion 11 adapted to engage the end of the stud 2. At its free end the plate 9 has inwardly extended flanges 12. A stiffening plate 15 is

secured upon the flanges 12, and a stiffening plate 14 is secured to the under side of the guard 9, there being a space between the plates 14 and 15.

In the space between the plates 15 and 14 a latch 16, in the form of a plate, is mounted to slide. The latch 16 includes a body 17, located at the inner end of the latch. The body 17 is wide enough so that it extends entirely across the plate 9 from side to side as indicated in Figure 3 of the drawings. The latch 16 comprises a head 18 and the body 17, and a reduced neck 19 connects the head and the body. The inner transverse edges of the head 18 form shoulders 20. The latch 16 is slid by means of a button or projection 22 which moves in slots 23 formed in the outer stiffening plate 14, and in the guard 9, as shown in Figure 2. There are openings 21 in the stiffening plates 14 and 15, and these openings 21 are in registration with each other.

A strap 24 may be disposed in the form of a loop, and be placed on the stud 2 of the base member 1, the strap passing through the opening 4 of the part 3, and between the arms 5, it being observed that both the loop 3 and the arms 5 are arranged at an angle to the base member 1 as shown in Figure 2 of the drawings.

The guard 9 is swung over on top of the base member 1, on the hinge formed by the part 10. The depressed portion 11 of the guard 9 engages the end of the stud 2 and holds the strap on the stud. The finger 6 and the keepers 8 pass through the aligned openings 21 of the plates 14 and 15. By means of the button 22, the latch 16 can be shoved in from the position shown in Figure 1, and then the shoulders 20 of the latch 16 will engage with the keepers 8 and prevent the guard 9 from swinging open with respect to the base member 1.

Having thus described the invention, what is claimed is:

In a device of the class described, a base member provided with a stud, the base member being supplied at one end with a loop and being provided at its opposite end with approximately parallel arms having inwardly extended fingers terminating in overhang-

ing keepers which extend toward each other, the keepers being located in a plane approximately parallel to the plane in which the extensions are located, a guard mounted at one end to swing on the loop, the guard cooperating with the stud in holding a strap, the guard being provided at its free end with inwardly extended flanges, a stiffening plate secured upon the flanges, and a stiffening plate secured to the under side of the guard, there being a space between the plates, the stiffening plates having registering openings, a latch mounted to slide in the space between the plates, the latch including a body located at the inner end of the latch, the body being wide enough so that it extends entirely across the guard from side to side, the latch comprising a head and a reduced neck connecting the head with the body, the inner transverse edges of the head forming shoulders, the fingers and the keepers extending through the openings, and the shoulders engaging the keepers.

In testimony that I claim the foregoing as my own, I have hereto affixed my signature.

ROBERT M. SWINDLER.
